UNITED STATES PATENT OFFICE

PAUL F. COX, OF CHICAGO, ILLINOIS, ASSIGNOR TO GOSS PRINTING PRESS COMPANY, OF CHICAGO, ILLINOIS, A CORPORATION OF ILLINOIS

INK FOUNTAIN ADJUSTING DEVICE

Application filed July 17, 1930. Serial No. 468,671.

This invention relates to the inking mechanism of web printing presses; and is a novel tool whereby the fountain screws may be adjusted by the operator from the side of the press without his having to reach into the press in order to do so. The tool is particularly designed for use in connection with web printing presses of the so-called "Cox-O-Type" which have two type beds, one above the other, and cylinders which are reciprocated over the beds, and the web is led from the lower bed up to and over the upper bed. Such presses are provided with ink fountains at the outer end of the press adjacent each bed, and the web in passing from one bed to the other passes around the outer ink fountain of the upper bed; and ordinarily if it becomes necessary to adjust such ink fountain, in case the ink is not properly supplied, it has been necessary to stop the press and break the web opposite the fountain to enable the operator to get access to the fountain adjusting screws.

The object of my invention is to provide means whereby the operator may adjust the fountain screws without having to stop the press or break the web in order to get at the fountain screws. The invention provides a novel tool whereby the keys of the upper fountain which are located behind the web can be operated from the side of the press. With such tool the adjusting screws of the upper ink fountain can be operated while the press is running, rendering it unnecessary to stop the press, and obviating the necessity of breaking through the web to reach the keys of such fountain.

The tool in brief comprises a spindle having a square socket in its end to engage the squared end of any fountain screw. The outer end of the socket is enlarged to facilitate engaging the spindle with the screw. This spindle may be driven by any suitable means preferably by a bevel gear and pinion, and in the construction shown the pinion has a long shaft of hollow light steel tubing which serves as a handle for operating the tool.

In the accompanying drawings I have illustrated a practical embodiment of the inven-

tion, and will explain the device with reference thereto, and summarize in the claims the novel features of construction and combination of parts for which protection is desired.

In said drawings:

Fig. 1 is a top plan view of the tool engaged with a fountain adjusting screw.

Fig. 2 is a side view of the device.

Fig. 3 is an inner face view of the rear casting.

Fig. 4 is an end view of the tool.

Fig. 5 is an enlarged sectional view on the line 5—5 of Fig. 4.

The tool shown comprises a front member 1, a rear member 2, a screw engaging spindle 4, gears 3 and 5 and an operating handle 5a. The front member is preferably U-shaped in cross section and has upper and lower flanges 1a which are slightly flared away from each other at each end of the body 1. The body 1 is provided at center with a circular opening 1b to accommodate the end of the screw engaging spindle 4. The body is also provided at one end with upper and lower lugs 1c. The rear member 2 has a sleeve portion 2a in axial alignment with the opening 1b, and a second sleeve portion 2b at almost right angles to sleeve 2a and connected therewith by a curved portion 2d. Sleeve 2b is provided with lugs 2c, corresponding to lugs 1c, and which may be fastened thereto by bolts, as indicated in the drawings, or other fastenings to securely and rigidly connect the members 1 and 2 when the parts are properly assembled.

The sleeve 2b is perpendicular to the axis of the sleeve 2a but is preferably slightly inclined relative to the body 1, as indicated in the drawings. Rotatably mounted in the sleeve 2a is a spindle 4 which has a flange 4a on its outer end and its inner end 4b is slightly reduced and on this reduced portion is tightly fitted or secured a bevel gear 3, which lies between the body 1, and the sleeve 2a and the gear 3 and collar 4a engage opposite ends of the sleeve 2a and prevent longitudinal play of spindle 4 in the sleeve 2a, and also retains the gear 3 in proper position.

The front end of the spindle 4 projects into the opening 1b, and in this end of the spindle

is a socket 4b which is adapted to engage the end of a fountain adjusting screw S as indicated in Fig. 1. The ends of the screws S should be angular, and socket 4b similarly 5 angular in cross section so that when the stub shaft is engaged with the end of a screw it cannot rotate thereon, and if the spindle is then turned the screw will be turned. The ends of the screws S are preferably beveled, 10 as indicated at s, and the outer end of the socket 4b is preferably flared as indicated at 4c, to facilitate engagement of the spindle with the end of a screw S.

Rotatably mounted in the sleeve 2 is a shaft 15 5a on the inner end of which is fastened a beveled gear 5 which meshes with the gear 3. The shaft 5 should be made long enough to enable the operator to reach any screw in the length of the fountain from the side 20 of the press. The outer end of the shaft 5a may be provided with a crank if desired (not shown) so that it can be readily turned.

Operation

25 In using the tool the operator holding the handle 5a moves the U-shaped member 1 along the row of screws until it is opposite the screw which he desires to adjust, the U-shaped body 1 serving to keep the tool in alignment with the screws as the tool is moved from one screw to another. When the tool is moved opposite the proper screw the funnel end of the spindle 4 will engage the end of the screw and the spindle is turned 30 until the socket in the spindle aligns with the end of the screw, then the tool is pressed forward to cause the spindle to slip over the screw as shown in Fig. 1. The spindle can then be turned to tighten or loosen the fountain screw by properly rotating handle 5a.

With this device the operator can readily control the upper fountain screws or inner fountain screws of the inking mechanism of a flat bed web press without having to stop 45 the press, break the web, or having to manually reach into the press.

I claim:

50 1. In a tool of the character specified, a support having flanges adapted to guide and support the tool on the fountain screws, a spindle rotatably mounted in said support having a socket adapted to engage the end of a screw, said guide flanges projecting beyond the end of the spindle, a handle connected with the support, and means for rotating the spindle.

55 2. An ink fountain adjusting tool comprising a guide member having opposite flanges 60 adapted to guide and support the tool in engagement with the fountain screws, a spindle rotatably mounted on said member and having a socket adapted to be engaged with a screw, a gear mounted on the spindle, a handle connected with said member, and a pinion

on said handle operatively engaged with said gear.

65 3. An ink fountain screw adjusting tool; comprising a front member having opposite flanges adapted to guide and support the tool in engagement with the fountain screws, a rear member attached to the front member and having a first sleeve and a second sleeve at an angle to the first sleeve, a spindle journaled in the first sleeve and adapted to be engaged with a screw, a gear mounted on said spindle, a handle rotatably mounted in the second sleeve, and a pinion mounted on the handle operatively engaging said gear. 70

75 4. A fountain screw adjusting tool comprising; a front member having opposite flanges adapted to guide and support the tool in engagement with the fountain screws and having an opening, a rear member attached to the front member and having a sleeve in 80 alignment with the opening and a second sleeve at an angle to the first sleeve, a spindle journaled in the sleeve opposite the opening and extending thereinto, said spindle having a screw engaging socket in its front end, a gear mounted on said spindle, a handle rotatably mounted in the other sleeve, and a pinion mounted on the handle to operatively engage 85 said gear. 90
